UNITED STATES PATENT OFFICE.

JOHN W. LAUREN, OF CHICAGO, ILLINOIS, ASSIGNOR, BY MESNE ASSIGNMENTS, TO STERLING WIRE MACHINERY COMPANY, OF STERLING, ILLINOIS, A CORPORATION OF ILLINOIS.

WIRE-DRAWING MACHINE.

Application filed March 8, 1920. Serial No. 364,154.

This invention relates to wire drawing machines of the type in which the wire operated upon is reduced in diameter a number of times by being successively passed 5 through a series of dies in one continuous drawing process.

In machines of this kind positively rotated drums are provided for drawing the wire through the dies. Since the drums 10 are rotated at fixed speeds relatively to each other variations in the speed of travel of the wire produces slippage of the latter over the surface of the winding drums. This slippage produces disadvantageous 15 results since not only is the wear on the drum considerable but also the coating of the wire is injured, thereby making it difficult to produce good wire.

A further trouble often experienced with 20 wire drawing machines is that the wire as first formed is not perfectly cylindrical and may have a feather along one side. If such a wire is drawn through a die it tends to cut grooves in the die.

One of the principal objects, therefore, 25 of the present invention is to provide means for varying the speed of the drums in accordance with the tension in the wire to avoid such slippage.

An important object of the invention is 30 to rotate the wire as it passes through the die to equalize the wear on the latter and produce a more uniform and satisfactory product.

A further object of the invention is to 35 provide means for preventing irregular jerky movements of the drums due to backlash in the driving connections therefor or other causes.

Another object of the invention is to 40 provide improved means for stopping the machine should the wire break, become tangled or for other reasons.

A further object of the invention is to 45 provide improved means for threading a wire through the various dies and starting the machine in operation upon a new coil of wire.

An additional object of the invention is 50 to provide threading means which may be driven when the rest of the machine including the drawing drums is stationary so as to prevent the drums from rubbing the wire

when the latter is drawn through the dies for winding around the drum and incidentally protecting the men from injury, 55 which is not possible should the drums be in constant rotation.

Other and further important objects of this invention will be apparent from the 60 disclosures in the drawings and specification.

The invention (in a preferred form) is illustrated in the drawings and hereinafter more fully described.

On the drawings:

Figure 1 is a side elevation of a machine embodying the features of the present invention.

Figure 2 is a plan view of the machine.

Figure 3 is a section on the line 3—3 of 70 Figure 2.

Figure 4 is an end view of the machine.

Figure 5 is a section on the line 5—5 of 75 Figure 2.

Figure 6 is a section on the line 6—6 of 75 Figure 2.

Figure 7 is a section on the line 7—7 of 80 Figure 2.

Figure 8 is a detail sectional view showing a part of the belt shifting mechanism.

Figure 9 is a detail view showing trip mechanism for the belt shift.

Figure 10 is a further detail view of the belt shifting mechanism.

Figure 11 is a section on the line 11—11 85 of Figure 2.

Figure 12 is a detail view taken from the side of the machine opposite that illustrated in Figure 1 showing the arrangement of belts and pulleys.

Figure 13 is a section upon the line 13—13 90 of Figure 9.

As shown on the drawings:

A coil of wire 1 is arranged upon a suitable non-rotatable support 2 and the wire 95 3 therefrom is led vertically upwards to a guide pulley 4 on the machine. As each turn of wire is lifted off the coil and passed

around the pulley 4, the wire twists through 360° so that the wire is given simultaneously a longitudinal and rotary movement. From the pulley 4 the wire passes around two pulleys 5 and 6 and thence to a die 7. The wire is drawn through this die by a drawing drum 8, around which the wire is coiled several times to give the desired fric- 100 105

tional engagement therewith. Next the wire passes in succession over each of the tension pulleys 9, guide pulleys 10, through dies 7 and around the drums 8 to a guide pulley 11 to a collecting drum 12. Guards 107 may be provided for retaining the wire in engagement with the drawing drums 8.

These parts are all carried by a frame 13 having supporting legs 14 and 15. Adjacent the front end of the machine is located the main driving shaft 16 mounted in bearings 17 and 18 on the frame. On this shaft are arranged fast and loose pulleys 19 and 20 adapted to be driven alternately by a belt 106. Means not shown may be provided for controlling the movement of the belt 106 to start or stop the machine independently of the fast and loose pulleys 19 and 20.

On the end of the shaft 16 is secured a pinion 21, which drives a gear 22 on one of the hollow shafts 23 which drive the drums 8. The first of these shafts is connected by a chain 124 and sprockets to the second shaft and the latter is arranged to drive the third and fourth shafts and also the shaft 24, which drives the collecting drum 12, by means of three superimposed belts shown in Figure 12. The first belt passes around the pulleys 27 and 28, the second over pulleys 26, 27 and 28, and the third over pulleys 25, 26, 27 and 28, so that all four pulleys are driven simultaneously and may be tightened by a single tension pulley. By using three superimposed belts backlash is avoided. This is an important feature since jerky movements of the drum shafts are very liable to break the wire. The sprockets and pulleys on the winding drum shafts are made of progressively decreasing diameter so that the speed of the corresponding shafts increases progressively as the wire is progressively decreased in diameter and increased in length by the action of the dies thereon.

The pulley 28, for driving the winding drum 12, is mounted on the shaft 24, to the end of which is secured a bevel gear 100. In mesh with the gear 100 is a second bevel gear 101 attached to the lower end of the vertical shaft 102, which drives the drum 12. A pulley 108 may be mounted on the shaft 24 for driving additional machines if desired.

The method of driving the drums 8 from the shafts 23 is shown more particularly in Figure 5. To the drum 8 a shaft 29 is secured which passes through the hollow shaft 23 and is rotatable relatively thereto. Mounted on this shaft is a differential 30, one pinion 31 of which is secured to the end of the shaft 23, while the other pinion is attached to the shaft 29. The differential spider 32, which carries the planetary pinions 33, is surrounded by a drum 34 for

the application of a brake band 35 thereto. With this arrangement it will be evident that the shaft 23 may rotate without driving the drum 8, the pinions 33 merely rolling around the pinion 32 without producing rotation of the latter. If, however, the brake band is tightened around the drum 34, the drum 8 will be caused to rotate and if the pressure on the brake band is sufficient to lock the drum 34, the shaft 29 and the drum 8 will rotate at the same speed as the shaft 23 though in the opposite direction.

The application of the brake 35 is controlled by the tension in the wire as it passes from one die to the next. For this purpose a series of pairs of standards 36 are mounted on the frame 13 connected at their upper ends by brackets 38, through which passes a horizontal bar 37. This bar is braced at its front end by rods 39 and 40 to give adequate support for the pulley 4, which is mounted on a bracket 41 secured to the forward end of the bar 37.

Blocks 41 are slidably mounted on the standards 36 and on each block is journaled one of the pulleys 9, over which the wire 3 passes. Normally these blocks are held at the top of the standards by chains 42, which pass upwardly over pulleys 43 secured to the brackets 38 and then downwardly with the lower ends of the chain attached to weights 44. Each weight 44 is mounted on the end of a lever 45 secured at its other end to a rock shaft 46. An adjustable counterweight 109 is also arranged on each lever 45. On the rock-shaft 46, is mounted an arm 47 connected to one end of the brake band 35, while the other end of the latter encircles the shaft 46. If desired to obtain a differential action on the brake band instead of attaching one end of the latter to the shaft 46, such end may be connected to the lever 45 at a distance from the axis of the shaft 46 somewhat less than the distance between the latter and the point of connection of the brake band to the arm 47. With this arrangement if the chain 42 is drawn upwardly the brake band 35 is tightened around the drum of the differential. Hence, when the tension in the wire passing over any one of the pulleys 9 increases, the latter is drawn down, thereby increasing the pressure of the corresponding brake band and raising the speed of the drum 8 associated therewith.

As the speed of the drum increases the tension in the wire decreases until equilibrium is reached.

Preferably means are provided for throwing the machine out of operation should the wire break and also when the end of the coil of wire has been reached. Conveniently this is accomplished by mounting the last die of the series on a support 48 (Figure 9) mounted on the upper end of a rocker arm 130

77. A spring 49, secured at one end to the frame and at the other end to the support 48, normally holds the support at the forward end of its path of movement. When, however, wire is being drawn through the die 7 by the collecting drum 12, the traction of the wire overcomes the tension of the spring and moves the support to the rearward end of its path of movement. When the wire breaks or the end of the coil is reached the traction of the wire on the die ceases, and the support returns to its original position under the action of the spring 49.

15 Various means may be provided for causing forward movement of the support under the action of the spring 49 to throw the machine out of operation. In the construction shown a belt-shifter 50 is provided mounted 20 on a rod 51 (Figure 4) longitudinally reciprocable in bearings 52 on the upper ends of standards 53 secured to the frame 13. Parallel to the rod 51 is a bar 54 slidable in brackets 55 attached to the frame 13 and rigidly connected to the rod 51 by a member 56. The bar 54 is reciprocated by means of an arm 57 mounted on a shaft 58 journaled on the frame and formed with a slot 59 at its upper end for engagement with a pin 30 60 on the bar 54.

Secured to the shaft 58 is an arm 61 carrying a counterweight 62 at its outer end which tends to throw the belt shifter towards the loose pulley. Parallel to the shaft 35 58 is a rod 63 secured to the former by a series of arms 64 extending from the shaft 58 in the opposite direction to the arm 61 so that pressure of the foot on bar 63 will lift the counterweight and throw the belt 40 onto the fast pulley 19. In order that the shifter 50 may be held opposite the fast pulley against the action of the counterweight, a bar 65 (Figure 10) is pivotally connected to the arm 57 by a pin 66. On 45 the under side of this bar are arranged projections 67 and 68 adapted to engage pins 69 and 70 on the frame. When the belt shifter is opposite the fast pulley the projection 67 is in engagement with the pin 69. If now this bar is lifted until the parts 67 and 69 no longer engage, the counterweight will move the arm 57, bar 65 and other parts to the left (Figure 10) until projection 68 55 engages the pin 70. In this position the belt shifter is opposite the loose pulley.

The bar 65 is raised automatically whenever the wire breaks and the support 48 for the last die moves forwardly. For this purpose a rod 71 (Figure 9) is provided having an end portion 72 extending under the bar 65, and a cam surface 73 adapted, when the rod 71 is reciprocated forwardly, to push the bar 65 upwardly until free of the pin 69. At its rear end the rod 71 is provided with 60 two notches 74 and 75 adapted to engage

alternatively with a pin 76 on the rocker arm 77. The notch 74 has a vertical face on its forward side so that when the pin 76 is in engagement therewith movement of the support 48 under the action of its spring 49 70 will cause the rod 71 to move forwardly. The notch 75, however, is formed with an inclined face on its forward side so that the pin 76, when in engagement therewith, will merely lift the rod 71 instead of sliding it forwardly as the support 48 moves in that direction. A latch 78 pivoted to the frame at 79 is provided with a shoulder 80 adapted to engage a pin 81 on the member 77 and thereby releasably prevent movement 80 of the support 48 by the spring 49. When, however, the rod 71 is in operative position with the pin 76 in engagement with the notch 74, the forked end 82 of the latch 78 rests upon a cam surface 83 of the rod 71 85 and is thereby held in elevated position with its shoulder 80 clear of the pin 81. When the rod 71 is in inoperative position the latch drops down into the position shown in dotted lines in Figure 9.

Frequently it happens that the wire tangles as it leaves the support 2, and it is desirable that the machine be stopped as soon as that occurs. Accordingly a ring or loop 84 is provided beneath the pulley 4, through which ring the wire is threaded. If the wire tangles it is held by the ring 84 and the tension in the wire passing around the pulleys 5 and 6 increases. The pulley 5 is mounted on a swinging arm 85 provided with a rearward extension 86 (Figure 8), to which is attached a cord 87 passing around a pulley 88 and supporting a counterweight 89 at its lower end. Normally the tension of the wire is insufficient to move the arm 85 upwardly against the pull of the counterweight. When, however, the tension increases owing to the wire becoming entangled against the ring 84, the arm 85 is drawn upwardly and pulls the cord 87 with it until a ball 90 engages the forked end 91 of a bell crank 92 and lifts the other end of the latter thereby releasing the belt-shifting mechanism.

Difficulty is often experienced in threading the wire through the dies 7 and around the drums 8. Special means are, therefore, provided for this purpose. In the construction shown these means include an endless chain 93 passing around sprockets 94 (Figures 3, 6 and 7). One of these sprockets is mounted on a shaft 103 having at its other end a gear 104 in mesh with a pinion 105 rigidly connected to the loose pulley 20 so that when the belt 106 is in engagement therewith the chain is driven by the sprockets 94.

The driving mechanism of the pulling-in device is mounted on the loose pulley so as to prevent the drums from rubbing the wire when the latter is drawn through the

dies for winding around the drum. In other words, the drawing-in is done while the rest of the machine is at a standstill thereby incidentally protecting the men 5 from injury, which is not possible should the drums be in constant rotation.

To one part of this chain a wire clamping device 95 is secured so that the wire may be drawn along the machine. In threading 10 the wire through the machine the first die 7 is secured to a bracket 96 adjacent the forward end of the path of travel of the chain 93. The end of the wire is now passed around a guide pulley 111 through the die 15 and there secured to the clamp 95 and drawn rearwardly by the chain. Then the wire is disconnected from the clamp and the latter is connected again to the wire at a point adjacent the die. This operation is 20 continued until sufficient wire has been drawn through the machine to be lapped several times around the first winding drum 8 over the first tension pulley 9 back to the guide pulley 111. When this has been ac- 25 complished the die 7 is returned to its normal position and the wire which has been drawn therethrough is passed around the drum 8 and pulleys 9 and 111. After this has been done the second die 7 is placed 30 on the bracket 96 and wire is drawn there- through as before. These operations are continued until the wire has been threaded through all of the dies and lapped around the collecting drum 12. 35 The operation is as follows: A coil 1 of wire 3 is placed on the support 2 and the end of the wire 3 is threaded through the ring 84 around pulleys 4, 5 and 6 and through the first die 7. The latter is se- 40 cured to the bracket 96 and after the end of the wire has been passed through the die it is attached to the clamp 95 on the chain 93. The chain is then placed in operation by bringing the belt 106 in engagement with 45 the loose pulley 20. After sufficient wire has been drawn through the first die the latter is replaced in its normal position. Then the wire is passed around the drum 8 and pulleys 9 and 111. Next the second 50 die is placed on the bracket 96 and the wire drawn therethrough as before. 55 After the wire has been threaded all through the machine the belt shifter 50 is placed so as to retain the belt 106 in engage- 60 ment with the fast pulley 19. The drawing drums 8 and the collecting drum 12 are then driven by means of gears 21 and 22, chain 24 and the belts passing around the pulleys 25, 26, 27 and 28. The speed of 65 operation of each of the drawing drums is regulated automatically by the tension in the wire as it passes around each tension pulley 9. If the tension around one pulley should increase the block 41, on which the pulley 9 is mounted, is drawn downwards pulling

the lower end of the chain 42 connected thereto upwardly. As this chain is connected to the weight on the brake lever 45, the tension of the brake band 35 around the drum 34 of the corresponding differential 70 30 is increased. As a result the drawing pulley is speeded up and the tension of the adjacent portion of the wire thereby automatically decreased.

So long as wire is being drawn through 75 the last die 7 its support 48 is held in rear- ward position against the tension of the spring 49. When an end of wire, which may be either a broken end or the end of the coil 1, passes through the last die 7, the traction 80 on the die suddenly becomes zero and the support 48 is drawn forwardly by the spring 49. This causes the rod 71 to slide forward and by its cam surface 73 lifts the latch 65 out of engagement with the pin 69, thereby allowing the counterweight 62 to move the belt shifter 50 so as to throw the belt 106 onto the loose pulley 20, thereby stop- 85 ping the machine.

I am aware that numerous details of construction may be varied through a wide range without departing from the principles of this invention, and I therefore do not purpose limiting the patent granted otherwise than indicated by the appended 90 95 claims.

I claim as my invention:

1. Wire drawing apparatus comprising a plurality of dies, a plurality of drawing drums, a driving shaft for each drum, a separate frictional driving means for each shaft, a differential between each of the shafts and its drum, a brake acting on the differential spider, and means controlled by the tension in the wire for varying the pressure of the brake and thereby controlling the speed of rotation of the corresponding drum. 100 105

2. Wire drawing apparatus comprising a plurality of dies, a plurality of drawing drums, a driving shaft for each drum, a separate frictional driving means for each shaft, a differential between each of the shafts and its drum, a brake acting on the differential spider, an idle pulley for the passage of the wire therearound in its passage from one 110 115 drawing drum to the next drum, a movable support for the idle pulley, and a connection between the support and said brake whereby variations in the tension of the wire produce changes in the pressure of the brake and thereby control the speed of rotation of one of the drums.

3. Wire drawing apparatus comprising in combination a plurality of dies, a plurality of drawing drums, a separate frictional driv- 120 125 ing means for each shaft, a driving shaft for each drum, a differential between one of the shafts and its drum, a brake acting on the differential spider, a movable tension device for the wire arranged between the last-men- 130

tioned drum and a drum adjacent thereto, and means controlled by the movement of said tension device for controlling said brake and so varying the speed of said drum.

5 4. Wire drawing apparatus comprising a plurality of dies, a plurality of drawing drums, a driving shaft for each drum, a separate frictional driving means for each shaft, a differential between one of the shafts and 10 its drum, a brake acting on the differential spider, a movable tension device for the wire arranged between the last-mentioned drum and the drum adjacent thereto, and a connection between said device and said 15 brake whereby variations in the tension of the wire produce changes in the pressure of the brake and thereby control the speed of rotation of one of the drums.

5. Wire drawing apparatus comprising a 20 plurality of dies, a plurality of drawing

drums, an endless chain, a driving shaft, fast and loose pulleys on said shaft operatively connected to the drawing drums and chain respectively, and means for attaching a wire to one part of the chain and thereby 25 drawing the wire through each die in succession prior to the engagement of the wire with the corresponding drawing drum.

6. Wire drawing apparatus comprising a driving belt, a driven shaft, fast and loose 30 pulleys on said shaft, a belt shifter, counter-weighted means normally adapted to move the belt shifter opposite the loose pulley, a latch for holding the belt shifter opposite the fast pulley, and means for releasing the latch 35 whenever the tension in the wire exceeds a predetermined value.

In testimony whereof I have hereunto subscribed my name.

JOHN W. LAUREN.
